UNITED STATES PATENT OFFICE.

VERNA A. NEVINS AND VERGIL O. NEVINS, OF HOOKER, OKLAHOMA.

GUARD FOR GASOLINE LAMPS.

Application filed September 8, 1921. Serial No. 499,201.

To all whom it may concern:

Be it known that Verna A. Nevins and Vergil O. Nevins, citizens of the United States of America, residing at Hooker, in the county of Texas and State of Oklahoma, have invented new and useful Improvements in Guards for Gasoline Lamps, of which the following is a specification.

The object of the invention is to provide an efficient guard for the mantle for use in connection with gasoline or similar lamps as a means of protecting the same and adapted for use either in connection with or independently of a shade, to protect the mantle against drafts or sudden changes of temperature and contact with adjacent objects; and with this object in view the invention consists in a construction and combination of parts of which a preferred embodiment is shown in the accompanying drawings, wherein:

Figure 1 is a side view partly in section of a lamp having a guard embodying the invention.

Figure 2 is an inverted plan view of the guard.

Figure 3 is a plan view of the same.

The guard 10 embodying the invention consists of wire cloth or gauze or like preferably metallic reticulated material which in the construction illustrated is of conical form, being reduced in diameter toward its upper end and is provided with a bottom closure or lid 11 hinged as at 12 to the wall 35 of the guard and provided at a diametrically opposite point with a catch or fastener 13 by which it may be secured in its closed position. This guard is provided at the center of its upper end with an opening 14 for the reception of the stem 15 which projects upwardly from the fuel tube 16 and is held in place thereon by collars or nuts 17, so as to enclose said stem and the fuel tube 16 together with the mantle 18 which depends 45 from the burner portion 19 of the fuel tube.

The fuel tube as in the ordinary practice serves as a vaporizing retort by reason of being exposed to the radiant heat of the flame in the mantle and is in communication with the supply tube 20 forming the standard of the lamp and rising from the base 21 which constitutes the reservoir or tank having the usual filler tube 22.

In order to permit of the opening of the guard to light the gas at the mantle the lid 55 or cover is diametrically slotted as shown at 23 with an enlargement 24 at its inner end to embrace the fuel tube.

Moreover as illustrated in the drawing a shade 25 may be employed in connection 60 with the lamp to cover the guard but may be omitted without detracting from the efficiency of the guard, said shade as in the ordinary practice being attached to the hanger rod 26 by which the lamp when desired may be suspended from an overhead support.

Having described the invention, what is claimed as new and useful is:—

The combination with a gasoline lamp 70 having a fuel tube provided with a downwardly directed burner orifice and an adjacent mantle, and having an upwardly extended stem terminating in a hanger and provided with means for supporting a shade, 75 of a mantle guard of wire screen provided at its upper end with an opening for the reception of the said stem and depending in enclosing relation with said mantle and the adjacent portion of the fuel tube, said guard 80 being provided at its lower end with a hinged lid or cover for giving access to the interior of the guard and means for normally holding the lid or cover in its closed position.

In testimony whereof they affix their signatures.

VERNA A. NEVINS.
VERGIL O. NEVINS.
